UNITED STATES PATENT OFFICE.

GEORGE E. GOUCHER, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,085, dated July 25, 1882.

Application filed June 16, 1882. Term of patent 14 years.

To all whom it may concern:

Be it known that I, GEORGE E. GOUCHER, of the city and county of Philadelphia, in the State of Pennsylvania, have invented and produced a new and original Design for Fringes, of which design the following is a specification.

The accompanying drawing is a side view of a section of fringe embodying and illustrating my design, which consists in a fringe having a heading, A, to which is attached a series of chenille pendants, B, which are ornamented by being formed of threads which are of uniform color, but present two independent graduations, shadings, or variations of depth or intensity of said color in their length—that is to say, the pendant at its point of connection with the heading will be of the deepest shade of the color selected, which color will be gradually lightened in depth or tone from the heading to or near the middle of the pendant. At this point the color of the pendant

will be of similar deep tone to that at the heading, and will be similarly gradually lightened in tone to or near the free end. The direction of graduation of each of the above shadings may be reversed without changing the general effect. In the pattern illustrated an end swell, tip, or enlargement, b, of different color, is added, which, however, does not constitute an essential part of the design, and may be omitted without changing the characteristic feature thereof.

I claim—

A design for fringe, consisting of pendants presenting two independent graduations, shadings, or tintings of color between the heading and their free ends, substantially as set forth.

GEORGE E. GOUCHER.
